UNITED STATES PATENT OFFICE.

LEWIS C. BAYLES, OF EASTON, PENNSYLVANIA, AND ARTHUR E. PETERS, OF LITTLETON, COLORADO, ASSIGNORS TO INGERSOLL-RAND COMPANY, OF JERSEY CITY, NEW JERSEY, A CORPORATION OF NEW JERSEY.

SHANK AND BIT PUNCH.

Application filed January 17, 1923. Serial No. 613,125.

To all whom it may concern:

Be it known that we, LEWIS C. BAYLES, a citizen of the United States, a resident of Easton, Northampton County, and State of Pennsylvania, and ARTHUR E. PETERS, a citizen of the United States, a resident of Littleton, Arapahoe County, and State of Colorado, have invented a certain Shank and Bit Punch, of which the following is a specification accompanied by drawings.

This invention relates to machines for punching hollow objects, but more particularly to a fluid actuated shank and bit punch of the hammer type, for punching the shanks and bits of hollow drill steels, and is in some respects like the machine disclosed in Letters Patent No. 1,463,134 granted July 24, 1923, to Harry V. Haight, for shank and bit punch, with additional features.

The objects of the invention are to enable relatively hard and rapid blows of impact to be imparted to the pin for hammering the pin into the steel, and also produces blows of impact for hammering the pin out of the steel, substantially equal in force to those utilized for driving the pin into the steel.

Greater trouble has been experienced in driving the pins into and out of the shanks of the drill steel than into and out of the bits, principally because the pin must be driven considerably deeper into the shank in order to clear the hole and greater effort is also required to withdraw the pin. The hammer piston of our present device is adapted to strike a severe blow upon a forward anvil block holding the pin, and when the pin is to be driven out of the hole in the steel, the machine is so constructed that the hammer piston will strike an equally severe blow upon a rearward anvil block, which has been brought into the path of impact of the hammer, at the same time that the forward anvil block has been withdrawn from the path of impact.

In carrying out the invention, fluid actuated feeding means are provided for feeding the machine forward and for retracting the machine. Means are also provided for controlling the distribution of motive fluid to both the punching machine and the feeding mechanism and in the preferred form of construction, a valve controls the supply of

motive fluid through the agency of the ports and passages leading from the valve to both punching and feeding mechanisms, so that the operation of punching and feeding will be preferably controlled by the same valve.

The machine is shown in one of its preferred forms in the accompanying drawings, in which—

Figure 1 is a side view partly in longitudinal sectional elevation of our machine applied to a drill sharpener,

Figure 2 is an end elevation of the drill sharpener showing our machine partly in transverse sectional elevation,

Figure 3 is a top plan view of a drill sharpener with our machine applied thereto.

Figure 4 is an enlarged detail longitudinal sectional elevation of the punching mechanism,

Figure 5 is a view similar to Figure 4 with the parts in a different position,

Figure 6 is an enlarged detail longitudinal sectional elevation taken through the controlling valve of the machine,

Figure 7 is a detailed transverse sectional view of Figure 6 on the line 7—7, and

Figures 8 to 13 inclusive are diagrammatic transverse sectional views taken through the valve shown in Figure 6, illustrating different positions of the valve. In said views, Figures 8, 10 and 12 are taken on the lines 8—8 of Figure 6 and Figures 9, 11 and 13 are taken on the line 9—9 of Figure 6.

Referring to the drawings, the shank and bit punch is shown mounted on a drill sharpener for convenience of illustration. The drill sharpener is illustrated diagrammatically and comprises the base A and the cylinder B adapted to contain a fluid actuated piston for actuating the movable cross head C. The cross head is provided with the jaw member D, and the cylinder is provided with the stationary jaw member E, in the usual manner. A dolly device F is shown mounted on the arm G but as this dolly device forms no part of the present invention, it will not be further described. The drill sharpener and dolly device are controlled by the usual throttle valve handle H at the side of the drill sharpener.

Our improved shank and bit punch is mounted on the bracket J suitably secured in any suitable location to the side of the

drill sharpener, as by means of the bolts K. The punching mechanism is slidably mounted on the bar L which is preferably rectangular in cross section, and secured to the arms of the bracket J as by means of the bolts O.

The punching and feeding mechanism forms a unitary structure comprising the hammer cylinder P and the feed cylinder Q preferably formed in one piece, although these cylinders may be separate if desired.

The cylinder P of the punching mechanism is provided in this instance with the valveless differential reciprocating piston R having the head S, the rearwardly extending shank T and reduced neck U and suitable ports and passages are provided for the distribution of motive fluid in the cylinder for actuating said piston. The cylinder P is mounted between the front head V and the back head W, and the front head is preferably provided with the filler piece X. The heads V and W are secured to the cylinder P by the side bolts Y.

A front anvil block a is inserted in the front head V and a front cross head b extends over the anvil block and front head. Similarly at the rear end, a rear anvil block c is inserted in the back head W and a rear cross head d is located over the rear anvil block and rear head. The front and back cross heads b and d are spaced apart by means of the spacers e, which may be in the form of sleeves, and through bolts f passing through the spacing sleeves hold the front and rear cross heads b and d together. By means of this construction the front and back cross heads b and d may be bodily moved back and forth on the front and back cylinder heads V and W through a given distance.

In the present instance a guide or support g for the drill steel h is suitably carried on the feed bar L and may be adjusted forwardly and backwardly by means of the bolt j and slot k on the guide or support. The drill steel h is adapted to rest in the guide g in position to have the hole or bore of the drill steel opened by the pin o carried by the front anvil block a. For punching bits of drill steels, the guide g will be adjusted in the position shown in Figure 1, while for punching drill steel shanks, the guide will be adjusted nearer the punching mechanism since the pin must be driven further into the drill steel than in punching a bit.

The feed cylinder Q is provided with the piston p having the piston rod q which extends rearwardly through the feed cylinder and is secured to the feed cylinder back head s as by means of the nuts t. When fluid pressure is admitted to the space u in front of the piston p, the entire machine will be fed forward, in which case the space

v in the feed cylinder will be vented to atmosphere. For retracting the machine, the conditions are reversed and the front end u of the cylinder is vented to atmosphere while fluid pressure is admitted behind the piston p.

The control of motive fluid for the punching and for the air feeding mechanism is preferably effected by means of the throttle valve r mounted in the back head s and controlling the inlet w. This throttle valve r is preferably connected to be actuated by means of a hand lever x pivoted at y on the frame of the drill sharpener, provided with an operating handle z. A valve rod 2 pivoted at the point 3 to the lever x is also pivotally connected at the point 4 to an arm 5 connected to the throttle valve r, so that by manipulating the hand lever x, the throttle valve r may be rotated back and forth from neutral position, which is the position indicated in Figure 1 and in Figures 8 and 9. A retracting spring 6 is connected to the hand lever x at any suitable point 7 and also connected at any suitable point 8 to the punching mechanism. By manipulating the handle towards the drill sharpening machine, and against the tension of the spring 6, the controlling valve r will be rotated into a position to start the hammer of the punching mechanism and also start the machine feeding forward in order to drive the pin o into the drill steel h. When the shank or bit of the drill steel has been punched out, the operator removes his hand from the hand lever x and the retracting spring 6 retracts the lever x and throws the valve r to reversed position, in which case the air feed cylinder moves the machine rearwardly and the pin is driven out of the drill steel. When the punching mechanism approaches the rear end of the bar L, its initial position, an extension 9 on the rod 2 which connects the hand lever x with the valve arm 5 strikes against a stop 10 on the back head s and returns the valve lever x to neutral position thus cutting off the supply of motive fluid from both the feed cylinder and the hammer cylinder. This construction considerably increases the speed of operation of the machine and also serves to keep the punch from creeping forward along the bar L during the time that the drill sharpener is being operated and when the punching mechanism is not in use.

In the operation of the apparatus, let it be assumed that the controlling valve r is in neutral position with the valve arm 5 substantially vertical as indicated in Figure 1. This position of the parts is also indicated in Figures 8 and 9 diagrammatically. Motive fluid admitted through the inlet w may pass to the hollow bore 12 of the valve r through the valve openings 13, shown in Figure 6. The supply to the

hammer R of the hammer cylinder P is cut off, due to the closure of the passage 14 communicating with the valve chamber of the valve r. Likewise the supply of motive fluid to the air feed cylinder through either of the passages 15 or 16 is cut off, all as indicated in Figures 8 and 9, which are sections taken respectively on the lines 8 and 9 of Figure 6. The parts of the punching mechanism and of the feed cylinder will be in the positions indicated in Figures 1 and 4, with the front anvil block a in position to receive the blows of impact of the hammer piston R, while the rear anvil block 15 c will be out of the path of the hammer piston. By moving the hand lever x towards the drill sharpening machine, the valve r will be rotated into a position to admit motive fluid to the hammer cylinder 20 through the passage 14 and also admit motive fluid through the passage 15 to the forward end of the feed cylinder Q. The rearward end of the feed cylinder Q will be vented to atmosphere through the passage 25 16 and through a suitable passage in the valve r as indicated in Figure 6.

The machine will be fed forward and the pin o will be hammered into the hollow article or drill steel to be punched. When the 30 pin has been driven sufficiently far into either the shank or bit of the drill steel, the hand lever x is released and the retracting spring 6 retracts the lever in the opposite direction, thus reversing the throttle valve r 35 and moving it to the position indicated diagrammatically in Figures 12 and 13, in which case motive fluid is continuously supplied through the passage 14 to the hammer cylinder, but the functions of the passages 40 15 and 16 leading to the air feed cylinder are reversed and motive fluid is supplied to the passage 16 leading to the rear end of the feed cylinder, while the forward end is opened to atmosphere through the passage 45 15. As the feeding mechanism moves the machine rearwardly away from the drill steel, the front and rear anvil blocks a and c automatically assume the positions indicated in Figure 5, so that the hammer piston imparts blows of impact to the rear anvil block c 50 while the forward anvil block a is out of the path of the piston. As the extension 9 on the valve rod 2 strikes the stop 10, the valve is automatically returned to neutral position indicated in Figures 8 and 9 and the operation of the machine is stopped.

We claim:

1. In a fluid actuated machine for punching hollow articles, the combination with a cylinder and reciprocating piston bodily movable to and from the article to be punched, of an anvil block at each end of the cylinder, one anvil block being adapted to carry a pin, means for causing the piston to impart blows of impact to one or the other

of the said anvil blocks according to the direction in which the pin is to be driven, fluid actuated means for feeding the machine forwardly and for retracting the machine, manually actuated means for controlling the distribution of motive fluid to both the punching machine and the feeding mechanism, and means for automatically returning the said controlling means to neutral position when released from manual control. 70

2. In a fluid actuated machine for punching hollow articles, the combination with a cylinder and reciprocating piston bodily movable to and from the article to be punched, of an anvil block at each end of the cylinder, one anvil block being adapted to carry a pin, means for causing the piston to impart blows of impact to one or the other of the said anvil blocks according to the direction in which the pin is to be driven, fluid actuated means for feeding the machine forwardly and for retracting the machine, a manually actuated valve controlling the supply of motive fluid, and ports and passages leading from the said valve to both the punching machine and the feeding mechanism, whereby the operations of punching and feeding are controlled by the same valve, and means for automatically returning said valve to neutral position when the valve is released 95 from manual control.

3. In a fluid actuated machine for punching hollow articles, the combination with a cylinder and reciprocating piston bodily movable to and from the article to be punched, of an anvil block at each end of the cylinder, one anvil block being adapted to carry a pin, means for causing the piston to impart blows of impact to one or the other of the said anvil blocks according to the direction in which the pin is to be driven, fluid actuated means for feeding the machine forwardly and for retracting the machine, a valve controlling the supply of motive fluid, ports and passages leading from the said valve to both the punching machine and the feeding mechanism, whereby the operations of punching and feeding are controlled by the same valve, a hand lever for actuating said valve and means for automatically returning said valve and lever to natural position after the punching mechanism has been retracted from the work. 110

4. In a fluid actuated machine for punching hollow articles, the combination with a cylinder bodily movable to and from the article to be punched and valveless differential reciprocating piston in said cylinder having a head and a shank, of an anvil block at each end of the cylinder, one anvil block being adapted to carry a pin, means for causing the piston to impart blows of impact to one or the other of the said anvil blocks according to the direction in which the pin is to be driven, automatic fluid actuated feed- 120

- ing mechanism for the machine, and a motive fluid controlling valve for the punching mechanism and feeding mechanism mounted on the bodily movable portion of the machine.
5. In a fluid actuated machine for punching hollow articles, the combination with a drill steel clamp, of a cylinder and reciprocating hammer piston, an anvil block at each end of the cylinder, one anvil block being adapted to carrying a pin for opening the bore of a drill steel placed in the clamp, means for causing the hammer piston to impart repeated blows of impact to one or the other of the said anvil blocks according to the direction in which the pin is to be driven either into or out of the drill steel, fluid actuated means for feeding the machine forwardly towards the clamp and for retracting the machine away from the clamp, and means for controlling the distribution of motive fluid to both the hammer cylinder and the feeding mechanism, to cause the hammer piston to automatically deliver such repeated blows in rapid succession while feeding is taking place.
6. In a fluid actuated machine for punching hollow articles, the combination with a drill steel clamp, of a cylinder and reciprocating hammer piston, an anvil block at each end of the cylinder, one anvil block being adapted to carry a pin for opening the bore of a drill steel placed in the clamp, means for causing the hammer piston to impart repeated blows of impact to one or the other of the said anvil blocks according to the direction in which the pin is to be driven either into or out of the drill steel, fluid actuated means for feeding the machine forwardly towards the clamp and for retracting the machine away from the clamp, a common valve controlling the supply of motive fluid, and ports and passages leading from the said valve to both the hammer cylinder and the feeding mechanism, whereby the operations of punching and feeding are simultaneous and controlled by the same valve, both in the advancing and withdrawal movements.
- 50 7. In a fluid actuated machine for punching hollow articles, the combination with a drill steel clamp, of a cylinder and reciprocating piston, an anvil block at each end of the cylinder, one anvil block being adapted to carry a pin for opening the bore of a drill steel placed in the clamp, means for causing the hammer piston to impart repeated blows of impact to one or the other of the said anvil blocks according to the direction in which the pin is to be driven either into or out of the drill steel, fluid actuated means for feeding the machine forwardly towards the clamp, and for retracting the machine away from the clamp, a common valve controlling the supply of motive fluid, ports and pas-
- sages leading from the said valve to both the hammer cylinder and the feeding mechanism, whereby the operations of punching and feeding are controlled by the same valve, a hand lever for actuating said valve and means for automatically returning said valve and lever to neutral position after the punching mechanism has been retracted from the work.
8. In a fluid actuated machine for punching hollow articles, the combination with a drill steel clamp, of a cylinder and valveless differential reciprocating hammer piston having a head and a shank, an anvil block at each end of the cylinder, one anvil block being adapted to carry a pin for opening the bore of a drill steel placed in the clamp, means for causing the hammer piston to impart repeated blows of impact to one or the other of the said anvil blocks according to the direction in which the pin is to be driven either into or out of the drill steel, and automatic fluid actuated feeding mechanism for the machine, whereby the hammer piston will automatically deliver such repeated blows in rapid succession while feeding is taking place either forwardly or backwardly.
9. In an apparatus of the character set forth, the combination with a drill steel clamp, of a pin punch for opening the bore of a drill steel placed in the clamp, fluid actuated means for advancing the punch toward and withdrawing it away from the clamp, a hammer cylinder carried by said means having an anvil block at each end, one anvil block carrying the pin punch, a hammer piston in the cylinder for delivering repeated blows of impact to one or the other of the said anvil blocks when the punch is engaged in the bore of the drill steel, and means for supplying motive fluid to the hammer to cause it to automatically deliver such repeated blows in rapid succession.
10. In apparatus of the character set forth, the combination with a drill steel clamp, of a punch pin for operating in the bore of a drill steel clamped thereby, fluid operated means for automatically delivering rapidly repeated blows to the punch pin, comprising a cylinder having an anvil block at each end, one anvil block carrying the punch pin, and a hammer piston in the cylinder, and fluid operated means for advancing the punch pin toward the clamp and withdrawing it away from the same while the hammer is in action.
11. In apparatus of the character set forth, the combination with a drill steel clamp, of a punch pin for operating in the bore of a steel clamped thereby, fluid operated means for automatically delivering rapidly repeated hammer blows to the punch pin, comprising a cylinder having an anvil block at each end, one anvil block carrying the punch pin, and a hammer piston in the cylinder.

- cylinder, fluid operated means for advancing the punch pin toward the clamp and withdrawing it away from the same while the hammer is in action, means for supplying motive fluid to both the hammer and the moving means and a common valve for controlling the supply of motive fluid to both.
12. In apparatus of the character set forth, the combination of a drill steel clamp, a punch pin for operating in the bore of a drill steel clamped thereby, fluid operated means for automatically delivering rapidly repeated hammer blows to the punch pin, comprising a cylinder having an anvil block at each end, one anvil block carrying the punch pin, and a hammer piston in the cylinder, fluid actuated means for advancing the punch pin toward the clamp and withdrawing it away from the same while the hammer is in action, means for supplying motive fluid to both the hammer and the moving means, and a common valve for controlling the supply of motive fluid to both,

and permitting the simultaneous action both in the advancing and withdrawal movements. 25

13. In apparatus of the character set forth, the combination with a drill steel clamp, of a pin punch for opening the bore of a drill steel placed in the clamp, means positively connected to the punch, for moving the punch both toward and from the clamp, a fluid actuated hammer mechanism for delivering repeated blows to the punch when engaged in the bore of the drill steel, said mechanism comprising a cylinder having an anvil block at each end, and a reciprocating hammer piston in the cylinder, and means for supplying motive fluid to the hammer to cause it to automatically deliver such repeated blows in rapid succession. 30 35 40

In testimony whereof we have signed this specification.
